UNITED STATES PATENT OFFICE.

EBENEZER HILL, OF NORWALK, CONNECTICUT.

MEANS FOR UNLOADING AIR-COMPRESSORS.

No. 865,390.

Specification of Letters Patent.

Patented Sept. 10, 1907.

Application filed May 24, 1907. Serial No. 375,432.

To all whom it may concern:

Be it known that I, EBENEZER HILL, a citizen of the United States, residing at Norwalk, in the county of Fairfield and State of Connecticut, have invented a new and useful Means for Unloading Air-Compressors, of which the following is a specification.

This invention relates to a means designed to automatically operate to unload or relieve an air compressor of a part, or the whole of its work, according to the 10 degree of the pressure in the reservoir, receiver or system into which the compressor is forcing air.

The object of this invention is to provide an unloading means which will partially unload or relieve a compound air compressor without disturbing its mechanical balance or decreasing the relative efficiency 15 of the compressor.

The invention is illustrated in connection with a double-acting compound air compressor with an inter-cooler. For any given pressure of discharge from the 20 machine there is always a best, that is, a most efficient proportion between the size of the first and the second cylinders so that the work of compression shall be divided equally between the two cylinders. This best proportion between the sizes of the cylinders also 25 results in a certain best or most efficient pressure being carried in the intercooler between the cylinders—the pressure in the intercooler resulting from the fact that the second cylinder is not as large as the first cylinder, and that as the air from the first cylinder must all 30 pass through the second cylinder it must be reduced in bulk and thus its pressure increased.

If the first cylinder, by any system of unloading, does not take and force forward its full normal supply of air, and at the same time there is not a proportionate unloading of the second cylinder, the pressure in the 35 intercooler will fall, and the best conditions of the working of the compressor will be sacrificed. On the other hand, if the second cylinder only is partially unloaded, so that it will not take in and force forward 40 a full normal supply of air, the intercooler pressure will rise and the compressor will not operate under the most efficient conditions.

By means of the apparatus which forms the subject of the present invention both cylinders are unloaded 45 proportionately at the same time; that is—if the first cylinder is unloaded one-half, the second is also unloaded one-half; and this keeps the work done by each cylinder properly proportioned and the pressure in the intercooler the same as when both cylinders are fully loaded and are accomplishing a maximum amount of work.

In the form of the invention illustrated when both 50 cylinders are fully loaded the forward and return strokes during each revolution consume the same power, as the cylinders are double-acting, consequently when the first cylinder is half unloaded by rendering

one side of the cylinder ineffective, the complementary half of the second cylinder is unloaded at the same time, that is, if the first cylinder only works on the forward stroke, the second cylinder will only work on 60 the return stroke, thus preserving the mechanical balance of work during each complete revolution.

In the views, Figure 1 shows a portion of a compound double-acting air compressor provided with apparatus which embodies this invention, the said apparatus 65 being arranged to operate upon intake valves of the well-known Corliss type. The type of valves, however, is not essential to the invention, it only being necessary that there be an independent unloader for each end of each cylinder and that the unloaders on 70 the complementary ends of each cylinder be controlled at the same time or by the same control. Fig. 2 shows a sectional view of one of the air control valves used in this apparatus. Fig. 3 shows a section of a valve controlling mechanism used with this invention 75 and its relation to the intake valves at opposite ends of one cylinder. Fig. 4 shows a sectional view of the valve casing of an air control. Fig. 5 shows a plan of the valve casing. Fig. 6 shows a sectional view of a portion of an air control. And Fig. 7 shows a side 80 elevation of an air control valve.

In the compressor shown the large or first cylinder 1 is connected with the small or second cylinder 2 by means of the intercooler 3. The pistons in these cylinders are joined in the common manner and are 85 connected with the cross-head 4 which is reciprocated in the ways 5 by the usual engine mechanism. The first cylinder has Corliss intake valves 6 and 7, which are actuated by the crank or eccentric rod 8, and the second cylinder has similar intake valves 9 and 10, 90 which are actuated by the crank or eccentric rod 11.

When the machine is operating under normal conditions air is taken in by the first cylinder and forced through the intercooler to the second cylinder and then forced from the second cylinder through the discharge 95 pipe 12 to the receiver or reservoir 13 of the system to be supplied with air under pressure.

A pipe 14 leads from the receiver to an air control 15 which opens when the pressure in the receiver reaches a predetermined degree. And a pipe with a branch 16 100 leads from this air control to a mechanism 17 that is adapted to affect the operation of the intake valve 6 at one end of the first cylinder. A branch 18 from the pipe leading from this air control communicates with a mechanism 19 that is arranged to affect the operation 105 of the intake valve 10 at the opposite end of the second cylinder. A branch 20 leads from the outlet of the first air control to the inlet of a second air control 21 and leading from this second air control is a pipe with a branch 22 which leads to a mechanism 23 that controls the effective action of the intake valve 7 of the first cylinder. A branch 24 leading from the outlet 110

pipe of the second air control communicates with a mechanism 25 that controls the effective action of the intake valve 9 of the second cylinder (Fig. 1).

When the pressure in the receiver reaches a predetermined degree it causes the first air control to open and allow the air to actuate the valve control 17 at one end of the first cylinder and at the same time to actuate the valve control mechanism 19 at the other end of the second cylinder. When these mechanisms are actuated by the air pressure that enters when the first air control opens, the intake valves on the opposite ends of the first and second cylinders are held open, and this cuts down the capacity of each cylinder one-half but does not change the proportions or theory of its working.

If the pressure falls sufficiently the mechanisms 17 and 19 retract and allow the valves to resume their normal operation. However, if the pressure rises, instead of falls, the second air control opens and allows the pressure to actuate the valve control 23 and simultaneously the valve control 25, which then act to hold open the intake valves 7 and 9 and thus render both cylinders ineffective or temporarily put them out of commission. When the pressure falls if both ends of the cylinders are unloaded the two valve control mechanisms on the opposite ends of the two cylinders that were actuated last to render ineffective those ends of the cylinders, are first relieved so those ends resume normal effective action, and as the pressure continues to fall the mechanisms at the other opposite ends of the two cylinders, that is, those that were actuated first are relieved so that those two ends are again brought into commission, allowing the compressor to resume full normal effective operation.

Each of the valve controls has a cylinder 26 in which is a piston 27 with a stem 28 that is adapted to be retracted into the cylinder by a spring 29, and forced out of the cylinder by air pressure back of the piston. When the air pressure back of the piston is sufficiently high to overcome the force of the spring the piston stem is thrust out so as to engage the latch 36 and cause it to disconnect the valve stem arm 31 from the eccentric rod arm 32 (Fig. 3), and then the reciprocation of the eccentric rod does not actuate the valve, but leaves it open in the position it occupied when the piston stem tripped the latch. When the pressure falls the spring retracts the piston stem and allows the latch to again connect the valve stem arm and the eccentric rod arm so that the reciprocation of the eccentric rod will again cause the valve to open and close. This control mechanism is fully described in Patent No. 844,802 of February 19, 1907, together with its action on the valve operating mechanism, and consequently is not described more in detail herein.

As previously stated the air pressure is admitted to the several cylinders of the valve controls by the action of the air controls referred to. Each of the air controls above mentioned has in a case 33, a cylindrical valve 34, that is normally held to a seat 35 by the pressure of a spring 36 on a stem 37 in the upper end of the air control. In this position the valve closes the inlet opening 39 to which the pipe from the source of pressure is connected. When the pressure in the inlet 39 overcomes the force of the

spring 36 the valve is lifted and moved into such position that air can pass through the seat, around the valve, and through the outlet 40 to which is connected the discharge pipe, that is, the pipe which leads to the valve controls. At the same time that the valve is lifted from the inlet seat it is closed against a seat 41 so as to prevent leakage through the casing which holds the stem and spring, and also so as to relieve the upper end of the valve of the pressure which is exerted on the lower end which assists in overcoming the thrust of the spring and renders the valve more sensitive. When the pressure drops sufficiently for the spring to close the valve the air in the pipes beyond the discharge outlets from the air controls, escapes by leakage and allows the springs to retract the valve control plungers and their stems which prevent the intake valves from operating normally. This air control is substantially the same as that shown and described in the Patent No. 844,802 above referred to.

When the first air control which is connected with the air receiver opens it unloads the distant ends of the large cylinder and the small cylinder. This cuts down the capacity of the compressor one-half but otherwise it does not change the proportions or the actions so that the mechanical balance of the work is preserved throughout the complete revolution. If the pressure continues to rise the air opens the second air control which is adjusted to operate under higher pressure, and this unloads the adjacent ends of the large cylinder and the small cylinder and renders the two cylinders for the time being completely ineffective. As the pressure falls the reverse action and order obtains and thus maintains the mechanical balance of work throughout each revolution.

In this application the valve controls for the opposite ends of the same cylinder are shown and described as independent and the air controls for the opposite ends of each cylinder are shown and described as working in sequence, or series, such an arrangement, however, is not claimed herein, for it is claimed in my pending application No. 375,431 filed co-incidentally with this application.

The invention claimed is:

1. The combination with a compound air compressor of means for temporarily rendering ineffective intake valves on opposite ends of the cylinders, and means for actuating the said valve controls on opposite ends of the cylinders simultaneously, whereby the cylinders are unloaded proportionately, substantially as specified.
2. The combination with a compound air compressor of means for temporarily rendering ineffective intake valves, and air controls for actuating the said valve controls at the complementary ends of the two cylinders simultaneously, substantially as specified.
3. The combination with a compound air compressor of means for temporarily rendering ineffective the intake valves at opposite ends of both cylinders, and air controls arranged to actuate the said valve controls on the opposite ends of the cylinders simultaneously, substantially as specified.
4. The combination with a compound air compressor of means for controlling the intake valves, and air controls actuated by the pressure produced by the compressor, one control operating to actuate the valve controlling means at complementary ends of both cylinders, and the second air control connected with the first air control and arranged to actuate the valve controlling means at the other complementary ends of both cylinders, substantially as specified.
5. The combination with a compound air compressor of an independent valve control for each intake valve, air

\$85,890

controls connected with each other and adapted to be actuated by the pressure produced by the compressor, one air control being arranged to act upon the valve controls at complementary ends of the two cylinders and the other air control being arranged to act upon the valve controls at the other complementary ends of the two cylinders subsequently to the action of the first air control, substantially as specified.

6. The combination with a compound air compressor of

valve controls for temporarily rendering ineffective intake 16 valves, and means actuated by air pressure which actuate complementary valve controls and unload the cylinders proportionately, substantially as specified.

EBENEZER HILL.
